Primary Examiner—Mitchell I Siegel
Attorney, Agent, or Firm—Cantor Colburn LLP[57] **CLAIM**

The ornamental design of golf club head, as shown and described.

DESCRIPTION

FIG. 1 is a top plan view of golf club head showing a first embodiment of my new design;

FIG. 2 is a front elevational view thereof;

FIG. 3 is a bottom plan view thereof;

FIG. 4 is a left side elevational view thereof;

FIG. 5 is a rear elevational view thereof;

FIG. 6 is a right side elevational view thereof;

FIG. 7 is a cross-sectional view taken along the line 7—7 of FIG. 2;

FIG. 8 is a bottom plan view of golf club head showing a second embodiment of my new design;

FIG. 9 is a left side elevational view of FIG. 8;

FIG. 10 is a rear elevational view of FIG. 8;

FIG. 11 is a right side elevational view of FIG. 8;

FIG. 12 is a top plan view of FIG. 8; and,

FIG. 13 is a front elevational view of FIG. 8.

The broken line showing of a fragmented shaft is for illustrative purposes only and forms no part of the claimed design.
